UNITED STATES PATENT OFFICE.

HERMANN SCHAEFFER, OF NEW YORK, N. Y.

DESIGN FOR A BADGE.

SPECIFICATION forming part of Design No. 31,514, dated September 19, 1899.

Application filed August 15, 1899. Serial No. 727,330. Term of patent 3¹ years.

To all whom it may concern:

Be it known that I, HERMANN SCHAEFFER, of the city of New York, borough of Brooklyn, in the county of Kings and State of New York, have invented and produced a new and original Design for a Badge, of which the following is a full, clear, and exact description.

Reference is to be had to the accompanying drawing, forming a part of this specification, in which the figure is a front view of a badge illustrating my design.

The leading feature of the design consists of the bust representation of a man, sur-

rounded by a wreath, at the lower portion of which is a spread-eagle, anchor-arms, and two crossed cannon, and at the top of the wreath the anchor-stock is represented with the ring.

I claim—

The design for a badge herein shown and described.

HERMANN SCHAEFFER.
